(57) **CLAIM**

The ornamental design for an electronic input device, as shown and described.

DESCRIPTION

FIG. 1 is a front perspective view of an electronic input device showing our new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The difference in shading in FIGS. 1 and 3-7 indicates a contrast of appearance and does not depict any particular color, texture, or material.
